UNITED STATES PATENT OFFICE.

GALLUS VON GLAUBITZ, OF MUNICH, GERMANY.

TOY AIRSHIP.

1,020,088.

Specification of Letters Patent. Patented Mar. 12, 1912.

Application filed May 25, 1911. Serial No. 629,514.

To all whom it may concern:

Be it known that I, GALLUS VON GLAUBITZ, chamberlain, a subject of the Grand Duke of Baden, and residing at Munich, 5 Germany, have invented certain new and useful Improvements in Toy Airships, of which the following is a specification.

The present invention relates to a toy air-ship consisting of a gas-bag in the shape 10 of a cigar on the style of the rigid dirigibles beneath which is secured a car with bunting, and which is held by a severally bifurcated cord.

In the accompanying drawing the present invention is exemplified and seen in side elevation.

The gas-bag *a*, which is of a cigar shape when filled is surrounded by two ring-shaped straps *b*, to which the holding cords 20 *c* and the cords *d* supporting the car *e* are attached. From the car *e* cords *f* are carried to the two ends of the gas-bag and their ends are there secured by means of

special caps *g*. The cords *f* are trimmed with bunting *h*. To the rear end of the gas- 25 bag is preferably attached an arrangement *i*, say a non-return valve, for refilling the gas and besides a device may be provided which will open at a given over-pressure.

The air-ship will not only serve as a toy, 30 but may also be used for advertising purposes.

I claim:

Toy air-ship, consisting of a gas-bag having the shape of a cigar when inflated, ring- 35 shaped straps on said gas-bag, caps on the ends of the gas-bag and cords attached to said straps and caps respectively and carrying the car and bunting.

In testimony whereof, I affix my signature in the presence of two witnesses.

GALLUS VON GLAUBITZ.
